BRAKE

Olaf Rasmussen, Sidney, Ohio, assignor to General Motors Corporation, Detroit, Mich., a corporation of Delaware

Application November 10, 1944, Serial No. 562,794

7 Claims. (Cl. 188—78)

This invention aims to provide a better brake for vehicles.

An object of the invention is to utilize as completely as possible the available annular surface of a wheel carried drum. Another object is to lessen the applying effort by taking full advantage of the drum rotation to apply the brake shoes to the drum. The arrangement involves multiple shoe assemblies, the spreading of one of which against the drum renders it a servo shoe operable to apply the others whereby relatively low rubbing speed between lining and drum is effective to check drum rotation. Another advantage resides in the less frequent need of adjustment by providing the adjustment on the servo shoe which does less of the braking. Less drum expansion will be caused because of less heat, and better dissipation of heat is provided than in the more conventional wheel brakes. Other objects and advantages will be apparent from a reading of the following description.

On the drawings, Fig. 1 is a view in transverse section of the novel brake as applied to a drum carried by a vehicle wheel. Fig. 2 is a section through the applying means. Fig. 3 is a view in elevation and partly in section showing the brake as seen from line 3—3 of Fig. 2. Fig. 4 is a view in elevation of the servo shoe assembly and Fig. 5 is a detail view of an anchorage member.

Referring to the drawings for a more complete description, numeral 7 is intended to represent an axle, a part of the wheel being indicated by 9. The brake drum carried by the wheel and axle is marked 11. A fixed axle housing is seen at 13. To it is secured by welding or otherwise a shouldered annulus 15 to which is secured as by fastening means 17 an anchor plate 19. A guard 21 may be used between parts 15 and 19, its flange 23 overlying the drum 11. This anchor plate is shown in perspective in Fig. 5. It is formed as a tube 25 with a flange 27 the latter being the part secured to the annulus 15 as stated above. The multiple shoe assembly includes three shoes, an intermediate shoe marked 29 and side shoes marked 31 and 33. The webs of these shoes rest on the anchor tube 25.

A cylinder 35 and piston 37 are located between one pair of ends of the central shoe 29, the cylinder and piston being notched as seen by Fig. 2 to engage the webs of the shoe parts. This spreading means is floating and not anchored as in the usual form of hydraulic brakes. Between the opposite ends of the shoe parts there is shown a conventional adjusting means marked 39 to spread apart these ends when the

lining becomes worn. A somewhat U-shaped spring 41 anchored in openings 43 in the shoe parts near the wheel cylinder restores the parts after being spread in the act of applying the brake. By reference to Fig. 5 there will be seen an elongated recess 45 in tube 25 of the anchor plate 19 to accommodate the wheel cylinder. A similar cutaway region 47 is provided for the adjusting mechanism 39. Brake shoes 31 and 33 at the sides of shoe 29 may be in the form of continuous bands broken only in the region where they are applied and anchored. The anchor cylinder 19 has two pairs of circumferentially spaced slots marked 51, 53 and 55, 57. Slots 51 and 53 receive lugs 59 and 61 of shoe 31 and slots 55 and 57 receive similar lugs on the web of shoe 33. A U-shaped spring 63 serves to hold these lugs in abutment with the ends of the slots as shown by Fig. 3. Projecting between the adjacent ends 10 of these side shoes are trunnions 65 and 67 on the wheel cylinder. They are suitably notched to engage the shoe webs as shown in Fig. 2. Trunnion 65 is provided with passages 69 and 71, the former to afford communication between 15 the fluid supply pipe 73 and the cylinder 35 and the latter for freeing the cylinder of air. A flexible boot may be used as shown at 75.

The operation may be briefly described. When fluid is forced into the wheel cylinder the shoe 29 engages the rotating drum and tends to rotate with it since the shoe is not anchored and the cylinder is floating. Its trunnions then move one or the other of the ends of the secondary shoes and thereby tend to carry around the secondary shoes. However, the end of each secondary shoe opposite the end pushed by the trunnion is anchored on the anchor plate. If, for example, and referring to Fig. 3, trunnion 67 moves clockwise 20 of slot 51 but the end of slot 53 stops lug 61. The anchoring of the side shoes obviously stops the rotation of the intermediate shoe.

The brake mechanism therefore uses to the greatest advantage the whole drum surface. 25 There is less wear on the servo shoe than on the side shoes so that there is less occasion for adjustment.

I claim:

1. In a brake, a drum, shoes arranged side-by-side in parallel planes and operable to engage the drum, means to spread an intermediate one of said shoes into drum contact, means whereby the movement of said intermediate shoe by contact with the drum expands other shoes one on each side of said intermediate shoe, means to

anchor one end of each of said side shoes, both side shoes being expanded substantially simultaneously whereby all three shoes are anchored and take part in retarding drum rotation.

2. In a brake, a fixed brake anchor having a tubular part, a wheel carried drum surrounding said anchor, three brake shoes arranged side by side between the drum and the anchor tube, means to spread the intermediate shoe into drum contact, means responsive to rotary movement of said intermediate shoe with the drum to actuate the shoes on each side of the intermediate shoe, anchor means for end parts of each of said side shoes, both side shoes being actuated substantially simultaneously whereby all three shoes cooperate in retarding drum rotation.

3. The invention defined by claim 2, said anchor having a plurality of slots and said side shoes having radial lugs extending within said slots and adapted to anchor on the ends thereof.

4. In a brake, a relatively fixed member, a rotatable drum, an anchor having a tube coaxially arranged within the drum and secured to

the fixed member, an intermediate shoe and side shoes having webs supported by said tube, means between the ends of said intermediate shoe to expand said shoe into contact with the drum to rotate therewith, lug and slot formations associated with said side shoes and tube to limit rotation of said side shoes and means associated with said expanding means and responsive to its rotary movement to spread said side shoes against the drum.

5. The invention defined by claim 4, said lug and slot means being provided at each end of each side shoe to facilitate braking in both directions of drum rotation.

6. The invention defined by claim 4, said relatively fixed member being an axle housing coaxial with and within said anchor.

7. The invention defined by claim 4, said expanding means being a hydraulic wheel cylinder and said last named means being trunnions extending laterally from said cylinder into the space between the ends of the side brake shoes.

OLAF RASMUSSEN.
